UNITED STATES PATENT OFFICE.

RAYBURN CLARK SMITH, OF PHILADELPHIA, PENNSYLVANIA, ASSIGNOR TO GEORGE W. SMITH & CO. INC., OF PHILADELPHIA, PENNSYLVANIA, A CORPORATION OF PENNSYLVANIA.

UNIT PARTITION AND WALL CONSTRUCTION.

1,176,692.

Specification of Letters Patent. Patented Mar. 21, 1916.

Application filed April 5, 1913. Serial No. 759,213.

To all whom it may concern:

Be it known that I, RAYBURN CLARK SMITH, a citizen of the United States, residing at Philadelphia, in the county of Philadelphia and State of Pennsylvania, have invented new and useful Improvements in Unit Partition and Wall Construction, of which the following is a specification.

This invention relates to a unit partition construction, and has for its object to provide a partition which is equally adapted for the construction of division walls of rooms, walls of booths, and for other temporary structures, and may be employed for various purposes that will suggest themselves to persons skilled in this line of work.

The partition has many novel features, among which may be mentioned portability due to its construction of unit sections, each 20 complete in itself with the necessary fastening devices permanently secured thereon. These several units comprise posts or pilasters, base sections, panels, mid-rail sections, cornice sections, and when desired sash sections. Also included in the unit sections are doors, door frames, and ceiling members. The units are of such size as to be easily 25 transportable, and all sections of like kind are made in standard size, and are interchangeable, making possible the easy increase or reduction in size of structures built of these units.

The partition is also sound and dust-proof. This is accomplished by forming 35 on the edges or connecting parts of the several units interchanging tongue and groove joints, and lining these joints with felt or like material; making the window sash double with an air space between the glass, and 40 by building up the panels with a central cellular or honey-comb construction.

When the partition is employed to form a closed room or booth with a ceiling, ventilation is obtained by hinging one or more 45 loose panels or sashes forming a part of said ceiling, so that said hinged members may be raised and lowered as desired.

Besides the several features of invention herein specifically mentioned other advantages will be brought out in the course of the description and suggested to those skilled in the art, the particular features of the invention being pointed out in the accompanying claims.

In the accompanying drawings: Figure 55 1 is a perspective view illustrating clearly the panel construction arranged to form a booth or room with a ceiling. Fig. 2 is a perspective view of a corner post unit viewed from the inner side. Fig. 3 is a perspective 60 view of one of the intermediate posts which are placed between the corner posts. Fig. 4 is a perspective view of a complete panel or section which extends between two of the posts, said panel or section being made up of 65 several units. Fig. 5 is a perspective view of the same panel, the unit members of which are shown separated. Fig. 6 is a vertical sectional view on the line 6—6, Fig. 1, looking in the direction indicated by the arrows. Fig. 7 is a horizontal sectional view 70 on the irregular line 7—7, Fig. 1. Fig. 8 is a vertical sectional view through a door and its frame on the line 8—8, Fig. 1. Fig. 9 is a perspective view of a portion of the 75 ceiling. Fig. 10 is a sectional view on the line 11—11 Fig. 9, showing a hinged sash which may be raised for ventilation purposes. Fig. 11 is a side elevation partly broken away illustrating the preferred form 80 of panel which may constitute a feature of the invention. This view is upon an enlarged scale. Fig. 12 is a vertical section showing a portion of the parts which are illustrated in Fig. 6, and showing details of 85 the arrangement for securing the sash. This view is upon an enlarged scale. Fig. 13 is a vertical section upon an enlarged scale showing a part of the lower portion of Fig. 6. 90

In the drawings, referring particularly to Fig. 1, 20 are the corner posts or pilasters, and 21 are the intermediate posts, between which posts are panels or partition sections 22, made up of the following parts: the base 95 unit 23, cornice unit 24, and an intermediate panel 25, which may extend from base to cornice if desired, or if preferred this space may be divided by a mid-rail unit 26, and the upper and lower divisions thereof filled 100 with panels 25, or a sash 27 may be placed in the upper division, as shown in the drawings. At any suitable point in the length or width of the structure a door 28 and door frame 29 may be placed between any 105 two columns, as shown.

Referring now to the detail construction of the several unit sections, the corner post 20

is L-shaped in cross section, and made of a number of narrow vertical strips of wood 30 glued or otherwise securely fastened together, and covered on their inner and outer faces with a laminated veneer 31. These strips 30 may extend the full length of the post, or be made of a number of shorter pieces. Posts constructed with a core of small strips of wood covered by veneering 10 are cheaper and stronger than when made of a single piece. The small strips, of which the posts are made, when fastened together in the manner shown, prevent springing and twisting of the post, and may be made of a cheap wood, which being covered by laminated veneer the outer layer of which may be of an expensive or rare wood, presents an ornamental and attractive post, which may be put up at a minimum of cost. 15 Vertically through the center of the post passes an opening 32, for electric wires. At the bottom of the posts are attached blocks 33 to form an ornamental base, which is finished with a scribe molding 34 that 20 rests upon the floor. At the top of the post or pilaster, both on its inner and outer sides, are moldings 35, which form a capital for the post, and over the spreading upper edges of these moldings are blocks 36 which cover 25 the ends of the post and the upper edges of the moldings. Extending from the bottom to the top of the post or pilaster in each edge, where it adjoins the panel sections 22, is a groove 37, and seated in the bottom of 30 this groove opposite the base 23, cornice 24, and mid-rail 26, are plates 38 having vertically elongated slots 39 therein to receive 35 fastening devices whereby the base, cornice, and mid-rail are connected firmly to the 40 column.

The strips of which the posts are made are preferably of rectangular horizontal cross section, and are preferably attached together with the flat sides of the strips 45 disposed at right angles to the plane of the wall which is being constructed. In other words the "flats" or flat sides of these strips are at right angles to the planes of the panels which assist in forming the wall. 50 The intermediate posts or pilasters 21 are made in the same manner as the corner post, but are made rectangular in form instead of L-shaped, and without the opening 32 for electric wires. The lateral edges of the intermediate posts have grooves 37 therein and also the slotted plates 38. 55

The base unit 23, cornice unit 24, and mid-rail unit 26, are each made of a plurality of narrow horizontal strips 50 secured together in the same manner as the strips of the posts or pilasters, and covered on their outer faces with laminated veneering. The ends of these several members are provided with tongues 40 which fit closely 60 within the grooves 37 of the post, and to

render these joints sound proof the outer edges of the tongues are covered with felt 41, or like material. Screwed to the bottom of the base unit 23 are two or more metal socket pieces 42 to receive dowel pins 43, which project upwardly from the floor. 70 Screwed to the outer faces of the tongues 40 are plates 44 from which project two key hooks 45, that engage the slotted plates 38 in the posts and hold the base unit and posts 75 securely together. The hooks 45 are preferably formed with downwardly projecting bills, the inner sides of the said bills being inclined. From this arrangement when a hook is passed through its corresponding plate and allowed to descend the inclined face of the hook strikes the edge of the plate and tends to draw the rail into close abutment with the post. The top of the base unit is grooved at 46 in a manner similar 80 to the groove 37 in the edges of the posts, and provided with two or more dowel pins 47, which project up from plates screwed in the bottom of the grooves.

The cornice unit 24, made as described, 90 of horizontal strips and laminated veneering is also provided with a spreading molding 48 at its upper edge similar to the capital molding on the posts or pilasters, and is finished by horizontal strips 49, as shown, 95 to cover the gaps between the upper edge of the molding and the horizontal strips of which the cornice is built. A small molding may be provided on the sides of the cornice at its lower edge. This, however, is a detail of ornamentation, which may be omitted, changed, or arranged in any manner in conformity with the taste of the builder. In the bottom of the cornice is made a groove 51 to receive a tongue on the sash or 100 panel as the case may be. Screwed to the bottom of the groove are two or more plates 51^a having holes therein for dowel pins on the panel or sash. The ends of the cornice are formed with tongues 52 similar to the 105 tongues on the ends of the base unit, and screwed to these tongues are plates 44 with key-hooks 45 whereby the cornice unit is attached to the slotted plates 38 at the top of the columns.

Mid-rail unit 26 made of horizontal strips of laminated veneering, as shown, has a groove in its upper and lower edges, in the bottom of which grooves are screwed plates provided with dowel pins to engage a tongue projecting from the sash unit, and the upper edge of the lower panel unit. The ends of the mid-rail section are provided with tongues and key-hook plates, as described 110 in connection with the base and cornice 115 units, and for the same purpose.

The panel unit 25 is of a rectangular form having a built-up interior and covered on both faces with laminated veneering 55. The inner structure of the panel is of cellu- 130

lar or honey-comb construction, and is made, as shown in Fig. 11, by a number of strips 56 extending transversely of the panel and spaced apart, between which strips are placed blocks 57 separated from each other to form cells 58 that provide air cushions between the two laminated panels and tend to prevent the passage of sound. Each strip 56 and block 57 has a dove-tailed groove 60 in one edge and a dove-tailed tongue 61 on its opposite edge, so that said parts when connected by these grooves and tongues form a strong rigid connection, which will not twist nor warp. The thickness of the panel 25 is just sufficient to enter neatly the grooves in the posts or pilasters, the base unit and the mid-rail unit, the outer edges of said panel unit being covered with felt or like material in the same manner as the 30 tongues on the other units, so as to secure a dust-proof and sound-proof joint.

The sash unit 27 is preferably made double, an outer member 62 and an inner member 63 forming the combined sash. The 25 outer member 62 is fixed in place within a frame 64, a rib 65 on the inner surface of said frame engaging a groove 66 in the edge of the outer member, the frame 64 is of the same width as the tongues of the several 30 members heretofore mentioned, and enters the grooves in the posts, cornice, and mid-rail. Dowel pins are secured on the top of the frame 64 to enter suitable holes in the cornice formed at the bottom of the groove 35 in the lower edge thereof. Felt packing 67 is placed on the outer edge of the tongue of the frame to make the joints between the sash and the other units dust and sound proof. The inner sash member 63 of the 40 sash has dowel pins 68 on its under side and a sliding pin 69 on its upper member operated by a thumb button 70 for engaging and disengaging said pin 69 with respect to the frame 64 when it is desired to remove the 45 inner member from the frame.

The door unit 28 presents the same external appearance as an ordinary panel door, the frame of which is built up of vertical and horizontal strips similar to the posts, 50 base and cornice, and covered externally with laminated veneering, as clearly represented in Fig. 8. The door is provided with a panel 72 and a sash 73, the former being made of cellular construction in the same 55 manner as the panel unit 25 and the sash made double like the sash 27. On each side of the door, and at the top is the door frame 29, from which project tongues 71 to enter grooves in the post or pilasters and in the 60 under edge of the cornice, suitable dowel pins being provided on the tongue at the top of the frame to enter holes in the cornice, as shown.

The several unit members of this partition or wall construction are all made to

standard sizes, like units having the same dimensions, and being interchangeable one with the other, so that no skill will be required to erect the parts, it being only necessary to place the posts in position, and then connect thereto the several unit members, the parts fitting accurately without requiring changes, alterations, or adjustment. The metal connections which fasten the several units together are all placed in the same position on the several units, and when fitted together hold the parts with all the rigidity of a solid structure. Loose fastening devices such as nails, screws, and the like, are entirely unnecessary in erecting the partitions, division walls, booths, or any other structure for which this invention may be used. If it is desired at any time to enlarge or diminish a wall, booth or room the same may be done by adding to or removing from 85 the structure one or more posts and panel members until the proper size desired has been reached.

When it is desired to fully inclose a space surrounded by a partition constructed as described, as for instance to place a top or ceiling over a booth or room, encircling strips of wood or narrow boards 75 are placed around the four sides of the booth or room at the top, and are supported by the projecting inner cornice molding, as shown in Fig. 6. These strips 75 have a projecting ledge 77 on their inner edges to support longitudinal cross members or beams 76, the ends of which are stepped to rest on the 100 ledges 77 of the strips 75. The strips or beams 76 have also projecting ledges 78 on which rest short bars 79 extending between the beams 76 and the surrounding members 75, so as to divide it up into a series of rectangular spaces 80, which are filled by panels or sashes as may be desired. To obtain ventilation, one or more of the panels or sashes in the ceiling will be hinged to its supporting frame so that it may be raised, as in 110 dotted lines, in Fig. 11. Any suitable means may be employed for securing the ceiling members upon the cornice units, or if desired these several members may be placed in position without fastening means, the 115 several parts fitting snugly in place will not require to be fastened. On the upper side of the encircling strips 75 and the cross beams 76 are formed grooves 81 in which may be placed electric wires. Holes 82 are 120 bored through said strips or beams through any one or more of which the wires may pass into the room or booth below.

What I claim is:—

1. A unit partition or wall structure comprising, in combination, a pair of posts having longitudinally extending grooves formed in their confronting faces, a pair of rails, locking members for the rails, locking members on the posts coöoperating with the lock- 130

- ing members for the rails and adapted to receive the latter when such rails are moved longitudinally for this purpose, the coöperating locking members being adapted to interlock by the lateral movement of the rails and to draw the posts and rails toward each other and the ends of the rails into relatively close contact with the posts, and a panel having vertical side edges seated in the grooves of the posts and having horizontal edges seated in grooves formed in the rails, the width of the panel being substantially equal to the length of the rails plus the depth of the grooves in the posts when the panel is assembled in the posts, so that such panel is clamped between the posts and the rails to substantially exclude the transmission of sound.
2. A unit partition or wall structure comprising, in combination, a pair of posts having longitudinally extending grooves formed in their confronting faces, a pair of rails having grooves formed in their confronting edges, a panel having vertical side edges seated in the grooves of the posts and having horizontal edges seated in the grooves of the rails, the width of the panel being substantially equal to the length of the rails plus the depth of the grooves in the posts when the panel is assembled in the posts, and coöperating locking members engageable by motion in two directions at an angle to each other and adapted when moved into interlocking engagement to draw the posts and the rails with the panel toward each other and into relatively close contact, the construction being such that the panel is tightly clamped between the posts and the rails to substantially exclude the transmission of sound.
3. A unit partition or wall structure comprising in combination a pair of posts, a pair of rails, connecting means at the ends of said rails for attaching said rails to said posts, connecting means at said posts adapted to receive the said connecting means of said rails by a longitudinal movement of the rail and adapted to interlock by a lateral movement of the rails with the rails and prevent the withdrawal of the rails, a panel, said posts having grooves on their adjacent faces receiving the edges of said panel, said rails and said panel having in-

terlocking means adapted to interlock by the said lateral movement of the rails toward the panel. 55

4. A unit partition or wall structure, comprising, in combination, corner posts formed of longitudinal strips connected together and having longitudinal grooves in their adjacent faces, the bottoms of said grooves having slotted plates mounted therein, a base rail adapted to lie upon the floor and having hooks adapted to be received in certain of said plates for holding said base rail between said posts, said base rail having a groove in the upper face thereof, a mid-rail parallel with said base rail having grooves respectively in its lower and upper faces and having hooks engaging certain of said slotted plates of said posts, a cornice rail having a groove in its under side and having hooks at the ends thereof engaging others of the said slotted plates, and panels between said rails and said posts having their edges received in the said grooves of said rails and said posts. 60 65 70

5. A unit partition or wall structure, comprising, in combination, corner posts formed of longitudinal strips connected together and having longitudinal grooves in their adjacent faces, the bottoms of said grooves having slotted plates mounted therein, a base rail adapted to lie upon the floor and having hooks adapted to be received in certain of said plates for holding said base rail between said posts, said base rail having a groove in the upper face thereof, a mid-rail parallel with said base rail having grooves respectively in its lower and upper faces 80 85 90 and having hooks engaging certain of said slotted plates of said posts, a cornice rail having a groove in its under side and having hooks at the ends thereof engaging others of the said slotted plates, and panels between said rails and said posts having their edges received in the said grooves of said rails and said posts, the ends of said rails having tongues fitting to said grooves of said posts. 95

In testimony whereof I have hereunto set my hand in presence of two subscribing witnesses. 100
